PETER S. ZONTOS, OF ST. LOUIS, MISSOURI, ASSIGNOR OF ONE-HALF TO DEMOS XELARAS, OF ST. LOUIS, MISSOURI.

ARTICLE HOLDER FOR POCKETS.

1,424,970.

Specification of Letters Patent. Patented Aug. 8, 1922.

Application filed January 3, 1922. Serial No. 526,836.

To all whom it may concern:

Be it known that I, PETER S. ZONTOS, a citizen of the United States, residing at St. Louis, Missouri, have invented a certain new and useful Improvement in Article Holders for Pockets, of which the following is a full, clear, and exact description, such as will enable others skilled in the art to which it appertains to make and use the same.

10 This invention relates to devices of the kind that are adapted to be arranged on the inside of a garment pocket to retain or hold an article in the pocket.

15 The object of the invention is to provide a device of the character referred to that is inconspicuous, inexpensive to manufacture and of such design that it can be used for holding a number of pencils or pens, or can be used for preventing a notebook or pocket-book from dropping out of the pocket of a garment.

20 Figure 1 of the drawings is a top plan view of an article holding device for pockets constructed in accordance with my invention.

25 Figure 2 is a front elevational view of said device.

Figure 3 is a sectional view, taken on the line 3—3 of Figure 2.

30 Figure 4 is a perspective view of a coat, illustrating my improved article holding device arranged in the breast pocket of the coat.

35 Figure 5 is a top plan view, illustrating the device used for retaining a notebook in a garment pocket.

Figure 6 is a top plan view of the device, illustrating it used for retaining a pocket-book in a garment pocket.

40 Figures 7 and 8 are top plan views, illustrating other forms of my invention; and

Figure 9 is a sectional view similar to Figure 3, illustrating another way of constructing the portion of the device that embraces the edge portion of the pocket in which the device is arranged.

45 My improved article holding device consists of a horizontally disposed member A of bar like form in general outline formed from a narrow strip of metal and adapted to be arranged on the inside of a pocket transversely of the pocket, a hook-shaped portion B on the member A that is adapted to embrace the upper edge portion of the

front wall or front side of the pocket inside 55 of which the member A is arranged, laterally-projecting arms at the opposite ends of the member A that project inwardly from the front wall or front side of the pocket, or, in other words, towards the body of the 60 person wearing the garment, and a resilient or flexible element D connected to the arms C and arranged parallel to and at the rear side of the member A, as shown in Figure 1. The member A, the hook-shaped portion 65 B and the arms C of the device are integrally connected together and are preferably formed from a sheet metal stamping that is light in weight, compact and inexpensive to manufacture, the hook-shaped portion B being so proportioned and designed that the member A will be positioned on the inside of the pocket in close proximity to the upper end of the pocket, as illustrated in broken lines in Figure 4. If desired, the member 70 A can be curved slightly in cross section, as shown in Figure 3, so as to impart strength to said member and also tend to cause the top and bottom edges of said member to bear against the inside face of the 75 front wall of the pocket in such a way as to insure the member A remaining in parallel relationship with the upper edge of the pocket. The inwardly-projecting arms C on the member A are preferably provided 80 with eyes 1 or hooks that receive the flexible or resilient element D of the device, and thus insure said element D remaining in spaced 85 relation to the member A. The element D may either consist of an endless band of 90 rubber stretched between the arms C, as shown in Figures 1, 5 and 6, it may consist of a coiled spring D', as shown in Figure 7, or it may consist of a corrugated or fluted element D², as shown in Figure 8.

95 If the device is to be used for retaining one or more lead pencils, pens or the like, the pencils are inserted between the element D and the member A, as shown in Figure 1, and force downwardly into the pocket of 100 the garment in which the device is arranged, the pressure which the element D exerts on the pencils being sufficient to prevent the pencils from accidentally falling out of the pocket. As the member A is of substantially the same length as the width of 105 the pocket, the device will accommodate a number of pencils or pens, thus overcoming

the necessity of equipping each pencil or pen with an individual holding device, as is now the universal practice.

While the device is particularly adapted for use in holding pens and pencils in operative position in the breast pocket of a man's coat, it is not limited to this use, but is capable of being used for retaining a notebook or the like in operative position in a pocket. Thus, as illustrated in Figure 5, the device can be used for retaining a notebook which is inserted in a pocket in such a way that it lies between the member A and the flexible element D of the device, the pressure which said element D exerts on the notebook insuring its remaining in operative position. Instead of inserting the notebook between the member A and the element D of the device, the notebook can be inserted between the element D and the rear wall or rear side of the pocket, in which event the element D serves to clamp the notebook against the rear side of the pocket. Still another way of using the device is to insert the article to be held inside of the pocket in such a way that the element D of the device extends transversely across the upper end of the article, as shown in Figure 6, wherein the article to be held consists of a pocketbook. In the form of my invention illustrated in Figure 7 the resilient or flexible element of the device that clamps the article to be held consists of a coiled spring D' stretched between the arms C on the member A and arranged in parallel relation to the member A. In Figure 8 I have illustrated still another form of my invention, wherein the clamping part of the device consists of a corrugated or fluted element D² arranged at the rear side of the member A and connected to the eyes 1 of the arms C at the ends of the member A. The hook-shaped portion D of the device that embraces the upper edge portion of the pocket inside of which the device is arranged may be constructed in various ways without departing from the spirit of my invention. It may consist either of a straight hook, as shown in Figure 3, that extends downwardly over the upper edge portion of the pocket, or it may consist of a hook B' provided with a reverse band or upturned portion 2, as shown in Figure 9, that has some resiliency so as to insure its firmly gripping the fabric that constitute the front side of the pocket in which the device is arranged.

Having thus described my invention, what I claim as new and desire to secure by Letters Patent is:

1. An article holding device for pockets consisting of a horizontally-disposed member adapted to be arranged on the inside of a pocket in proximity to the upper end of the pocket and formed from a narrow strip of metal that is provided at its ends with rearwardly projecting arms, a part on said mem-

ber that is adapted to embrace the upper edge portion of the pocket and retain said member in operative position below the upper edge of the pocket and a retaining element arranged parallel to said member and connected to the arms at the ends of said member.

2. An article holding device consisting of a horizontally disposed member formed from a narrow sheet metal stamping and provided with an upwardly projecting portion that is adapted to embrace the upper edge portion of the pocket in which said member is arranged and also provided at its ends with integral arms, and a retaining element arranged at the rear side of said member in parallel relation to same and connected to the arms on said member.

3. An article holding device for pockets consisting of a horizontally disposed sheet metal member of bar like form adapted to be arranged on the inside of a pocket below the upper edge of same, a hook-shaped portion on said member for embracing the upper edge of the pocket, rearwardly projecting arms arranged at the ends of said member, and a resilient element arranged at the rear side of the said member in parallel relation to same and connected to said arms.

4. An article holding device for pockets, consisting of a sheet metal member of bar like form adapted to be arranged horizontally on the inside of a pocket below the upper edge of same, means on said member for retaining it in operative position in the pocket, arms on said member equipped with eyes, and a flexible retaining element stretched between said arms and engaged with the eyes on same, said member being curved slightly in transverse cross section.

5. An article retaining device for pockets consisting of a horizontal bar like member formed from a narrow strip of sheet metal and adapted to be arranged on the inside of a pocket below the upper edge of same, a hook-shaped portion on said member for embracing the upper edge of the pocket, a pair of rearwardly projecting arms arranged at the ends of said member, and an endless rubber band arranged parallel to said member at the rear side of same and engaged with said arms.

6. An article holding device for pockets consisting of a horizontally-disposed bar like member constructed from a narrow piece of sheet metal and provided intermediate its ends with an integral, hook-shaped portion and provided at its extreme ends with integral, rearwardly-projecting arms equipped with eyes, a resilient element arranged at the rear side of said member and connected at its ends to the eyes on said arms, and a resilient extension on said hook-shaped portion, for the purpose described.

PETER S. ZONTOS.
